US0D1012197S

(12) **United States Design Patent** (10) Patent No.: **US D1,012,197 S**
Chatterjee et al. (45) Date of Patent: ** Jan. 23, 2024

(54) **CONTROLLER**

(71) Applicant: **Microsoft Corporation**, Redmond, WA (US)

(72) Inventors: **Monique Chatterjee**, Seattle, WA (US); **Matthew C. Harvey**, Seattle, WA (US); **Richard T. Hanks**, Arlington, MA (US)

(73) Assignee: **Microsoft Corporation**, Redmond, WA (US)

(**) Term: **15 Years**

(21) Appl. No.: **29/796,917**

(22) Filed: **Jun. 28, 2021**

(51) LOC (14) Cl. **21-01**

(52) U.S. Cl.

USPC **D21/333**

(58) **Field of Classification Search**

USPC D21/324, 333, 513; D14/356, 358, 383, D14/388, 400-401, 412, 554; D13/162

(57) **CLAIM**

The ornamental design for a controller, as shown and described.

DESCRIPTION

FIG. 1 is a front perspective view of a controller showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines depict portions of the controller that form no part of the claimed design.
